CLAIM

The ornamental design for vane for throwing wheel, as shown and described.

DESCRIPTION

FIG. 1 is a top plan view of a vane for throwing wheel embodying my new design;

FIG. 2 is a front elevational view thereof;

FIG. 3 is an end elevational view taken from the left of FIG. 1;

FIG. 4 is an end elevational view taken from the right of FIG. 1;

FIG. 5 is a rear elevational view; and

FIG. 6 is a top perspective view thereof.

Broken lines showing the base of the vane for the purpose of illustrating the environment of vane mounting.

FIG.1

FIG.2

FIG.3

FIG.4
